UNITED STATES PATENT OFFICE.

STEPHEN D. MURRAY, OF DALLAS, TEXAS.

COTTON-GIN.

1,186,425.

Specification of Letters Patent.

Patented June 6, 1916.

Application filed February 4, 1915. Serial No. 6,115.

To all whom it may concern:

Be it known that I, STEPHEN D. MURRAY, a citizen of the United States, residing at Dallas, in the county of Dallas and State of Texas, have invented new and useful Improvements in Cotton-Gins, of which the following is a specification.

This invention relates to an improvement in cotton gins and has particular reference 10 to the mote plate and also to the wind guard, the primary object of the invention being to provide simple and effective means whereby the mote plate may be readily and easily adjusted through the medium of a simple 15 construction and arrangement of parts.

A further object of the invention is to provide means for giving the mote plate a strong support and at the same time set up a tight joint or closure relatively to the lower 20 portion thereof and a conveying tube embodied in the gin organization and extending along the brush cylinder beneath the latter and thereby to cause the air currents laden with cotton removed from the saw 25 cylinders to be regularly directed into the said tube.

A still further object of the invention is to provide simple means for adjustably mounting the rear wind guard on a portion 30 of the cotton conveying tube and equip the said guard with means for readily adjusting the same.

With these and other objects and advantages in view the invention consists in the 35 preferred construction and arrangement of the several parts which will be more fully hereinafter described and claimed.

In the drawings: Figure 1 is a transverse vertical section through a portion of a cotton gin showing the improvements applied thereto, sufficient of the operating elements of the gin being illustrated to demonstrate the practicability of the improvements. Fig. 2 is a front elevation of a gin having a 40 portion thereof broken away to show the improved mote plate in its applied position. Fig. 3 is a detail perspective view of one end of the improved mote plate. Fig. 4 is a detail view of one of the brackets with which 45 the mote plate is adjustably associated. Fig. 5 is a transverse section through a portion of one of the brackets and the mote plate and particularly showing the means carried by the brackets for engaging the 50 mote plate and securing means for the latter. Fig. 6 is an enlarged detail transverse sec- 55 tion through the mote plate and a part of the supporting means therefor. Fig. 7 is an enlarged detail transverse section through the inner guard or plate. Fig. 8 is a detail view of the tool preferably used in adjusting the mote plate.

The improved gin is of the well known type embodying a longitudinal hollow member or tube within the body of the gin, as 60 disclosed for instance by my Patent No. 1,089,255, dated March 3, 1914, and comprises a frame 5 in which is mounted a roll box 6, a saw cylinder 7, a brush cylinder 8 arranged and operating in the usual manner, and a lint receiving tube or hollow member 9 disposed under the brush cylinder. This class of gins may be equipped with a hulling attachment or not, as may be desired. The tube or hollow member 9 has a 65 top inlet opening 10 directly under the brush cylinder 8; and disposed in the said opening 10 is a chute 11 which is arranged at an inward angle of inclination and projects into the upper portion of the said tube 70 or hollow member 9. The chute 11 embodies a bottom plate 12 which is extended outwardly from the forward edge of the opening 10 at an upward angle of inclination and is secured to the upper part of the body 75 of the tube or hollow member 9 adjacent to the said front edge of the opening 10 by an angular plate 13 having its two members respectively secured by bolts or fastenings 80 to the forwardly and upwardly extended 85 portion of the plate 12 and the adjacent part of the body of the tube or hollow member 9, as clearly shown by Fig. 1. The plate 12 terminates or continues in an obtuse 90 angular supporting member 15 which projects upwardly toward the saw cylinder 7 and is of such width as to reliably hold a mote board or plate 16 between the ends of the latter. The plate 12 extends longitudinally along the full length of the cylinder 95 and approximately from the inner surfaces of the end supports 17 comprised in the frame 5 of the gin, and the said supports are formed with upwardly and outwardly inclined slots 18. Secured to the outer sides 100 of the supports 17 and disposed at the same angle as the slots 18 are brackets 19, one at each end of the gin, each bracket having an outwardly projecting flat bearing flange 20 of the form particularly shown by Figs. 110 4 and 5, and on the rear side of each flange 20 is a lug or boss 21. The opposite extremi-

ties of the mote plate 16 project through and are movable in the slots 18, the said slots being long enough to compensate for the adjustment of the mote plate either upwardly or downwardly to a maximum extent. The opposite extremities of the mote plate 16 extending through the slots 18 to the exterior of the gin movably bear on the flanges 20, as clearly shown by Fig. 5, and in each mote plate extremity a slot 23 is formed and extends fully therethrough, the said slots 23 both having the same angle of inclination and in the same position relatively to the opposite extremities of the mote plate. The slots 23 in the opposite extremities of the mote plate are inclined upwardly or are in diagonal planes relatively to the mote plate extremities, and the lugs 21 movably engage said slots and extend entirely through the same. The adjustment of the mote plate is accomplished by any suitable tool that may be used to give the said plate a longitudinal shifting movement and operatively applied to either extremity of the plate, and a preferred form of such tool is a bar 24 having a reduced end 25 and a handle 26, as shown by Fig. 8. To render the use of the tool shown by Fig. 8, or any other analogous tool, practical in adjusting the mote plate 16, the latter has an upper opening 27 in each extremity, and the pointed end of the tool 25 is inserted in either opening in accordance with the desired direction of movement and adjustment of the mote plate 16 and pressed against a portion of the adjacent end support 17 so as to provide sufficient leverage for adjustment of the mote plate. The mote plate is frictionally held in its adjusted position without the use of fastening devices. When the mote plate 16 is adjusted it moves equally at opposite ends in view of the similar angle of the slots 23 and the corresponding angle of the lugs or bosses 21 projecting rearwardly from the flanges 20 of the brackets 19, and it will be impossible for the opposite extremities of the mote plate to shift irregularly for the reason that the opposite side edges of the lugs or bosses 21 closely engage the opposite side walls of the slots 23 and maintain a uniformity of movement at both extremities of the plate. The mote plate 16 is preferably made of a doubled piece of sheet metal of suitable thickness and proper dimensions bent into U-shape, the bent portion or top edge 22 being uppermost and the two free edges 28 being at the bottom. The side members of the plate are held spaced apart by interposed space members 31 positioned at the lower corners and secured by suitable fastenings 32, as clearly shown by Fig. 3. This formation of the plate 16 results in a rigid structure, and the lower edge of the plate 16 within the body of the gin is fully

open between the edges 28 to permit the entrance into the mote plate of the support 15 continued in this instance from and formed as the outer extremity of the plate 12, the said support 15 having the same angular position as the slots 18 and flanges 20 of the brackets 19. The mote plate 16 is slidable on the support 15 during its adjustment, and the support 15 adds its strength and rigidity to the mote plate or board, the two structures or the support 15 and bent plate 16 providing a thin yet stiff structure for the purpose specified. The mote plate 16 is adjusted relatively to the saw cylinder for a purpose which will be understood. As the outward extension of the plate 12 from the front edge of the opening 10 of the tube or hollow member 9 completely closes the space between the tube and the mote plate adjacent to the lower portion of the brush cylinder 8, the only vent means will be at the top edge 22 of the mote plate 16. It will also be seen that the mote plate 16 may be readily detached from the gin and easily replaced in operative position as occasion may require in disorganizing or in organizing the several parts of the gin.

At the rear edge of the opening 10 in the upper portion of the tube or hollow member 9, a wind guard or shield 33 is mounted, and consists of a doubled sheet metal plate of suitable thickness having lower rear extremities 34 bent to conform to the curvature of the rear edge portion of the opening 10 so as to embrace the adjacent edge portion of the tube 9, the main body of the wind guard or shield 33 projecting upwardly from the lower extremities 34 at an angle to the latter, as clearly shown by Figs. 1 and 7, and having the free edge thereof terminating close to the lower rear portion of the brush cylinder 8 and extending a considerable distance over the chute 11 below and particularly at the point where the chute enters at an angle to the upper portion of the tube or hollow member 9. The guard or shield 33 is slidably adjustable relatively to the portion of the tube or hollow member 9 which it engages, the said tube or hollow member being formed with elongated slots 35 at intervals and engaged by clamping bolts and their necessary accessories 36 which also pass through openings 37 in intermediate portions of the lower extremities 34 of the guard or shield. By this means the guard or shield may be shifted forwardly or rearwardly to modify the distance of the upper free edge thereof relatively to the brush cylinder.

The direction of movement of the brush cylinder 8 drives the air laden with the lint removed from the saw cylinder 7 downwardly into the tube or hollow member 9 through the chute 11, and the force im-

parted to the air currents laden with the lint causes the currents and the lint to whirl rapidly around the inside of the tube and impinge against the lower side of the chute and again mingle with the incoming air currents and lint, and the two portions of the air currents carrying the lint mingling at the inner lower extremity of the chute lend their force to each other and result in an effective transmitting action or movement thereof longitudinally along the tube or hollow member 9. This operation is largely due to the extension of the chute downwardly into the tube or hollow member 9 as shown, and the disposition of the chute at a downward angle below the inlet opening 10 is also effective in preventing the lint delivered into the tube or hollow member 9 from being drawn upwardly by and passing around with the brush cylinder, and the wind guard or shield 33 also materially obstructs any tendency of the cotton to pass over the opening 10 and upwardly and around with the brush cylinder 8, and, furthermore, said wind guard or shield breaks up any eddy currents at the rear portion of the brush cylinder that might otherwise be established. When this mote plate is properly adjusted, the motes as they are separated from the saw teeth by the brush cylinder will fall past the outer portion of the upper edge 22 of said plate and will not be carried along with the lint cotton to the chute 11 and into the tube or hollow member 9. The lint cotton delivered into the tube or hollow member 9 is conveyed or moved through the latter to any suitable point for further treatment, and the improved features hereinbefore noted and consisting of the novel form of adjustable mote plate and wind guard or shield will greatly add to the practical operation of the gin in effectively performing its ginning operation.

45 What is claimed is:

1. The combination with a cotton gin having saw and brush cylinders in the usual co-operating relation therein, of a mote plate having extremities extending through the ends of the gin and disposed at an upward and outward angle of inclination relatively to the cylinders, the gin ends and the plate being provided with interacting means for equally adjusting the plate upwardly or downwardly by longitudinal shifting movement of the plate in opposite directions.

2. The combination with a cotton gin having a frame and saw and brush cylinders in the usual co-operative relation therein, of a mote plate having extremities extending through the ends of the gin and disposed at an upward and outward angle of inclination and mounted to have upward and downward adjustment, the mote plate and gin frame being provided with similar interacting

means at opposite extremities for causing the same to move equally at both extremities and throughout the length thereof by longitudinal shifting movement of the plate in opposite directions.

3. The combination with a cotton gin having saw and brush cylinders in the usual co-operative relation therein, of an angularly disposed mote plate adjacent to the cylinders, the gin ends and extremities of the plate being provided with similar structural means for equally adjusting the plate upwardly or downwardly when the plate is longitudinally shifted in opposite directions by force applied to either end of the plate.

4. The combination of a cotton gin having saw and brush cylinders in the usual co-operative relation, the gin ends having similarly disposed angular slots with brackets on the outer sides of said ends close to the slots, and a mote plate having its opposite extremities projecting through the slots and movably engaging the brackets.

5. The combination of a cotton gin having saw and brush cylinders in the usual co-operative relation therein, the ends of the gin being provided with similarly disposed angular slots, brackets on the outer sides of the ends of the gin close to and arranged at the same angle as said slots and having supporting flanges with angularly positioned lugs, and an adjustable mote plate loosely projecting through the slots in the ends of the gin and having similar diagonal slots in the extremities thereof, the diagonal slots of the plate engaging and having the lugs projecting therethrough to guide the plate equally in its movement at opposite ends when adjusted.

6. The combination with a cotton gin having saw and brush cylinders in the usual relation therein, of a supporting means in the gin adjacent to said cylinders, and a mote plate consisting of a doubled thin metal sheet of U-shaped form with an opening between the edges of the side members, the mote plate being fitted over and frictionally engaging said supporting means and adjustable relatively to and from the saw cylinder transversely with relation to the supporting means therefor by shifting the plate on the said supporting means, the mote plate being uniformly movable throughout its length relatively to the saw cylinder by applying adjusting force to either end thereof.

7. The combination with a cotton gin having saw and brush cylinders in the usual co-operative relation therein and a tube lying within the body of the gin and provided with an upper inlet opening for receiving lint cotton, of a chute in said tube opening having a bottom plate extending forwardly at an upward angle and terminating in a support at a greater upward angle of inclination, and a mote plate movably held on

- the terminating support of said bottom plate and having the opposite extremities exterior of the opposite ends of the gin and provided with similar means for adjusting said mote plate either upwardly or downwardly and equally at opposite extremities and throughout its length by longitudinally shifting the mote plate.
8. The combination with a cotton gin having saw and brush cylinders in the usual co-operative relation therein and a tube lying within the body of the gin and provided with an upper inlet opening for receiving lint cotton, of a mote plate held in adjustable relation to the saw cylinder, and a shield extending upwardly and forwardly from the rear edge of the inlet opening of the tube toward the lower rear portion of the brush cylinder, the rear edge portion of the said inlet opening and the rear lower portion of the shield having means for adjusting the said shield.
9. The combination with a cotton gin having saw and brush cylinders in the usual co-operative relation therein and a tube provided with an upper inlet opening for receiving lint cotton, of a shield extending upwardly and forwardly from the rear edge of the inlet opening of the tube toward the lower rear portion of the brush cylinder, the rear edge portion of the said inlet opening and the rear lower portion of the shield having means for adjusting the said shield.
10. The combination with a cotton gin having saw and brush cylinders in the usual co-operative relation therein and a tube provided with an upper inlet opening for receiving lint cotton, of a shield extending upwardly and forwardly from the tube and consisting of a doubled thin metal sheet with the lower extremities shaped to conform to and embrace the rear edge portion of the tube, the rear edge portion of the tube and the lower extremity of the shield embracing the same having interacting means for permitting a shifting movement of the shield.
11. A cotton gin having a ginning cylinder, and a mote plate mounted to longitudinally move in the gin in opposite directions to simultaneously shift the same toward and away from the ginning cylinder.
12. A cotton gin having a ginning cylinder, a mote plate support adjacent to the said cylinder, and a mote plate doubled over on the support, the mote plate and parts adjacent thereto being provided with means whereby an endwise movement of the plate on the support will effect a lateral movement thereof to and from the ginning cylinder.

In testimony whereof I have hereunto set my hand in presence of two subscribing witnesses.
